SLALOM WATER SKI FOOT PAD

David Louis Senn, 1382 N. Hillside,
Orange County, Calif.

Filed June 12, 1961, Ser. No. 65,563

Term of patent 14 years

(Cl. D71—1)

FIG. 1.

FIG. 2.

FIG. 3.

FIG. 1 is a top plan view of a slalom water ski foot pad.

FIG. 2 is a side elevational view of the foot pad.

FIG. 3 is a longitudinal sectional view of the foot pad taken along line 3—3 illustrated in FIG. 1.

The bottom, not shown, is flat and plain.

I claim:

The ornamental design for a slalom water ski foot pad, substantially as shown and described.
